UNITED STATES PATENT OFFICE.

JAMES H. WESTCOTT, OF ONEIDA, NEW YORK, ASSIGNOR OF ONE-HALF TO
WESTCOTT CHUCK COMPANY, OF ONEIDA, NEW YORK, A CORPORATION
OF NEW YORK.

COMPOUND VISE.

No. 848,945.

Specification of Letters Patent.

Patented April 2, 1907.

Application filed January 25, 1906. Serial No. 297,725.

To all whom it may concern:

Be it known that I, JAMES H. WESTCOTT, a citizen of the United States, residing at Oneida, in the county of Madison and State of New York, have invented certain new and useful Improvements in Compound Vises, of which the following is a specification, reference being had therein to the accompanying drawings.

10 My invention relates to a compound bench-vise; and I declare that the following is a full, clear, concise, and exact description thereof sufficient to enable one skilled in the art to make and use the same, reference being had to the accompanying drawings, in which like letters and numerals refer to like parts throughout.

15 The purpose of my invention is to meet the requirements of such a device in ordinary work where there is likely to be a wide variety in size and shape of different articles to be manufactured. It is intended for convenient use in machine-shops and the like, being readily adaptable for different conditions.

20 In brief, it comprises the fixed abutment portions and the separate sliding portions, so constructed and mounted that both may be brought to hold the work against the fixed portions, being equally screwed up, or one 25 may be screwed fully against the work and the other screwed to hold it by intervening blocks.

25 In the drawings, Figure 1 is a plan view of the device, one of the sliding blocks and the top of the screw-journal being removed. Fig. 2 is an end view of one of the sliding blocks, and Fig. 3 of the end of the base on which it slides, part broken away. Fig. 4 is a top view of the block, showing one form of 30 it, which is shown in end view in Fig. 5. Fig. 6 is a side view.

35 The base portion is shown by A and has suitable means to secure it to the bench, and on it are the abutments or fixed blocks A' A'', arranged at an angle to each other and having the smoothed faces a and a'. The base is extended in arms, one opposite each block A' and A''. Each arm is slotted, as at a'', to receive the guides c on the sliding blocks 40 C, the blocks being held by screws inserted at the bottom through plates c'. Only one 45 such groove or slot in each arm may be used;

but on one of the arms the cuts are extended into the angle between blocks A' A'', so that one block can be forced close to its corresponding abutment or head. The block is screw-bored at c'' for the screw D, which is journaled in block d, having the cap d'. The turning of the screw moves the sliding blocks to and fro. The block has smoothed face ca. 50 Either or both arms may have these grooves extended to the desired point.

55 It will be seen that in handling small articles one of the blocks can be crowded into the angle to hold the work against the opposite block or head, while the other may be used to hold the work by intermediate blocks between the work and the sliding head. This gives one positive hold or grip on the work, which is a distinct convenience and one advantage of my improvement over the constructions where filling-blocks were needed against both sliding parts.

60 In Figs. 4 and 5 I illustrate a construction in which the sliding block is made up of parts. A portion C' is separate from main part C, the line of separation being angular to the edges, so as to secure a firm abutment, and it may also have the dovetail joint cb. (Shown by dotted lines in Fig. 4.) The vertical cut between C and C' is such as to include in the latter a threaded surface for screw D, and the guide c aids to hold block C' in place. The block C' may be secured by bolts or otherwise, as desired, and be given any suitable 65 form. By use of such a block without part C' the two sliding blocks can be brought to a much smaller field, as shown by dotted lines in Fig. 1. I indicate but a single form of such built-up block, expressing therein the 70 idea which may be given a variety of forms.

75 So, also, various modifications of the device are within the range of mechanical skill and also within the scope of the invention, though not shown or described herein.

80 Having described my invention, what I claim as new, and desire to secure by Letters Patent, is—

85 1. A combined vise having fixed abutments and sliding abutments, one opposite to each fixed abutment adapted to be passed into the field in front of the other sliding abutment, one of the said sliding abutments having its gripping portions made up of parts

interlocking and removable to reduce the face of said portions, substantially as described.

2. In a combined vise, sliding abutments and opposite fixed abutments, one of said sliding abutments being composite to present a gripping portion of reduced extent by the removal of certain of the component parts of said abutment, the said parts being

dovetailed into the main portion of the abutment and having a portion thereof in operative contact with the block-actuating means.

In testimony whereof I affix my signature in presence of two witnesses.

JAMES H. WESTCOTT.
